(57) **CLAIM**

The ornamental design for a X-ray imaging apparatus as shown and described.

DESCRIPTION

FIG. 1 is a perspective view of a X-ray imaging apparatus showing a first embodiment of our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a X-ray imaging apparatus showing a second embodiment of our new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines illustrate portions of the X-ray imaging apparatus that form no part of the claimed design.

1 Claim, 14 Drawing Sheets
